WELL DRILLING MAST

Delson Breeding, McCamey, Tex.

Application July 23, 1938, Serial No. 220,999

3 Claims. (Cl. 254—139)

This invention relates to improvements in well drilling apparatus, and its chief purpose is to provide a mast over which the various cables or lines can be run in drilling. As is more or less commonly known, the various cables used in raising and lowering the drilling tool, operating the bailer, raising and lowering casing, etc., must, obviously, be run over sheaves.

It is the current practice to provide these sheaves in appropriate places, but it is also current practice to place the sheaves virtually wherever it is most convenient to mount them. This practice has its particular advantage in the fact that it is a pure make-shift when erecting the drilling apparatus, but when the time comes for dismantling the latter, the taking down of the sheaves means doing all of the work over again when remounting the sheaves at another well.

From this it will be understood that the provision of a unit which when once constructed will serve for any number of wells, and mark a decided improvement in this branch of oil well digging. This unit comprises a portable mast which embodies all of the necessary sheaves for any conceivable kind of cable requirement.

A further provision comprises a safeguard against the damage which jumping cables can cause. With this preview in mind the objects of the invention are as follows:

First, to provide a heavy-duty mast for use in well drilling, having those structural features which permit the accommodation of any and all wire and other cables used for suspending the drill tool, pulling casing, operating the bailer, etc.

Second, to provide a mast of the foregoing type with a crow's-nest which serves the double purpose of bracing the top of the mast and providing a safe-guard for the operator who has to work out in the open at the top.

Third, to embody certain essential bracing in said crow's-nest, and to flare it downwardly so as to make room for the free running of the various lines at the front of the mast.

Fourth, to provide a mast wherein the sheaves are fully guarded so that the jumping of any cable can cause little or no damage.

Other objects and advantages will appear in the following specification, reference being had to the accompanying drawings in which:

Figure 1 is a perspective view of the upper portion of the mast, particularly illustrating the sheave and crow's-nest construction.

Figure 2 is a rear elevation of the mast mainly illustrating the system of bracing.

Figure 3 is a section taken on the line 3—3 of Fig. 1.

Figure 4 is a cross section taken on the line 4—4 of Fig. 3.

Figure 5 is a cross section taken on the line 5—5 of Fig. 3.

In carrying out the invention, the mast generally designated 1, comprises a pair of standards 2, 3. These standards preferably consist of heavy tubes, this being a necessity because of the great weights ultimately imposed upon them. Said standards are made perfectly rigid by a system of longitudinal and transverse bracing.

The transverse bracing comprises a series of 15 widely spaced tubes, the majority of which are designated 4 (Fig. 2). The uppermost one of this series is designated 5, the reason for the distinction being that the uppermost transverse brace 5 is secured at its ends 6 (Fig. 1) more nearly on the rear faces of the standards 2, 3. The remaining transverse braces 4 are situated between the standards and within the confines thereof, being attached to the confronting insides thereof by butt joints at 7.

The upright components 8 of this system of bracing consist of the pairs of tubes shown. These tubes reach between the transverse braces 4, 5, are attached thereto by butt joints 9, and lie within the confines of the standards. The 30 upright braces 8 taper upwardly. This arrangement offsets the places of attachment 9 with respect to the transverse braces 4, 5 according to the order illustrated in Fig. 2. The advantage of this offsetting lies in the added strength which 35 results from separating the places of connection of the longitudinal braces to the transverse braces.

Further strength is imparted to the mast by a plurality of cross braces 10. These, usually, 40 consist of solid bars. They are spaced at uniform distances apart, or approximately so, and in addition to their function of braces they provide ladder rungs upon which the workman can climb. All of the previously mentioned braces 45 are connected as indicated in the drawings by welding. The actual welds are not shown, but it will be understood that places such as 6 and 9 comprise welding points.

A crow's-nest construction or framing generally designated 11, is built into the top of the mast. This construction is involved in the bracing scheme and its main function is to strengthen the mast at the top to withstand the pressures imposed upon the various sheaves. Said framing 55

comprises pairs of tubes 12, 13 (Fig. 1) which extend out from the standards 2, 3 and constitute reach members as presently appears. The front of the mast designated 14, is identified by only 5 one cross tube 15, this tube connecting the ends of the pair of tubes 12. At the back of the mast the same pair of tubes is joined by a cross tube 16. The corresponding ends of the tubes 13 are joined by a cross tube 17. The tubes 15, 16 and 10 17 are thus spaced away from the standards 2 by the reach members 12, 13, the relationship of the cross members to the sheaves later described being such that a workman standing on a chosen one of the cross members will be in a position of 15 ready access to the sheaves for the adjustment of the respective cable. Bracing rods 18 are connected in this construction as shown, ultimately being secured to the standards 2, 3 as at 19.

A bracing tube 20 transfixes the standards 2, 3, 20 near the upper extremity and projects beyond the sides of the latter for slight distances at 21. Tapering braces 22 extend upward from this tube, being joined by a shaft 23 which is appropriately secured in sleeves 24 on top of the braces. The 25 shaft 23 carries what is known as a cat-head pulley 25. By virtue of the fact that the brace tube 20 is situated a slight distance below the extremities of the standards, the resulting structure provides recesses 26. These recesses as well 30 as projections 21 provide cable guards. If the cat-line should ever jump the pulley 25 it would be caught either by one of the recesses or one of the projections, thus lessening the chance of its falling down to the floor and injuring a worker. 35

A so-called upper shaft 27 is secured at 28 at its ends in sleeves 29 which, in turn, are fixed crosswise of the standards. At an appropriate distance below the upper shaft 27 there is a so-called lower shaft 30. This too is secured at 31 at its ends in sleeves 32 which are affixed crosswise of the standards. Said sleeves are welded in place. Their inner ends protrude at 32a (Fig. 3) to touch the hubs of the adjacent sheaves 40 presently described. Washers 32b are fitted upon the protruding ends 32a, and comprise flanges or wearing plates for the sheaves. The washers 32b are both welded to the sleeves and to the standards 2, 3 the welding material being fitted in at 50 32c (Fig. 5) to form a backing.

It will be observed that the lower shaft 30 is much heavier than the upper shaft 27. This provision is made because of the greater weights which are imposed upon the lower shaft. The 55 latter is medially braced by a pair of side plates 33. These are secured at 34 to the brace tube 20, from which said plates are pendent. They have holes at 35 sufficiently large to carry collars 36. They are enlarged at 37 so as to provide adequate 60 supports for the shaft 30 which projects through at this place. As already indicated, these plates take the strain off of the bottom shaft as they also do from the upper shaft 27.

A pair of pulleys 38 is mounted on the upper 65 shaft 27 between the collars 36. One or the other of these pulleys is used for the sand line. Generally only one pulley is used at a time, but it is preferred to have two at this place in order to meet an emergency. These pulleys have a 70 fairly wide space 39 between them. This space accommodates the top rim of the main or drill line sheave 40. Because of this arrangement the pulleys 38 are made to serve as guards for the main sheave. If the cable should jump it would 75 be deflected back into the pulley groove by the

lateral sheaves 38. The main sheave 40 is journaled on the lower shaft 40 between the enlargements 37.

Other pairs of sheaves 41, 42 are journaled on this shaft between the enlargements and the adjacent standards. These sheaves are used for various purposes such as supporting a ram line, casing line, etc. The side plates 33 and the adjacent standards 2, 3 serve as guards for the lines which run over these pulleys. 10

Reverting to the bracing, it is to be observed that the tapering braces 22 are supported by rods 43, which extend down to the cross tubes 15, 16. These rods are downwardly flared so as to make room for the free running of the various lines 15 mentioned at the front 14 of the mast. The plates 33, upon which much dependence is put, as already pointed out, are hung on rods 44 (Fig. 1) in addition to their attachment at 34. It will be perceived in Fig. 1 that the bracing which constitutes the crow's-nest 11 has various provisions for holding the cables should any one of them jump the respective pulley. The structure of the crow's-nest is also important in bracing the upper end of the mast where the main pressure occurs. 25 A further use of the crow's-nest is that of an anchorage for the guy wires 45. The manner of tying these on is merely suggested in Fig. 1 and in practice they can be tied on wherever the requirement dictates. 30

It is regarded as being of relative unimportance to point out in detail how the mast is mounted. The two standards 2, 3, will be mounted on an adequate foundation 46 (Fig. 2) somewhere within in the drill house 47. The mast must be mounted 35 adjacent to the hole and by preference it will lean slightly toward the front 14 and thus provide better clearance for the cables on the front side. When the latter are emplaced on the various sheaves the workman can lay boards across the various pairs of tubes 12, 13, and thus obtain 40 a good footing. He will be surrounded more or less by the adjacent bracing and thus safeguarded from falling.

I claim:

1. In a mast, a pair of standards, a brace tube transfixing the standards at its ends below the extremities of the standards thereby to define projections of the tops of the standards above the brace tube, upwardly extending braces affixed to 50 the brace tube in from the projections of the standards thus producing recesses, and a pulley journaled at the top of the braces, a cable jumping said pulley being caught in a recess. 45

2. A mast for use in well drilling comprising a 55 pair of standards, means spacing the standards laterally, said means including at least one shaft, at least one sheave adapted for the support of a cable, said sheave being mounted on the shaft and thus utilizing a part of the spacing means 60 for its journal, and a framing attached to the standards to strengthen them in the regions of the shaft and sheave against the stresses imposed by the cable, said framing consisting of a plurality of cross members situated parallel to the 65 shaft in proximity to the sheave so that a workman standing on a chosen one of the cross members will have ready access to the sheave for the emplacement of the cable, reach members extending out from the standards generally crosswise of the shaft and attached at their ends to the cross members thereby to space the latter away from the standards, and a bracing rod system connecting the cross members to each other and to the standards. 70 75

3. In a mast having a brace tube spacing a pair of standards and having parallel shafts attached to and spaced from each other along the standards; a single sheave on one shaft, a pair of pulleys on the other shaft, marginally overlapping the sheave and stationed at the respective

sides of the sheave, and a pair of side plates affixed to and pendant from the brace tube, providing journal supports for both shafts and being located close to the pulleys to prevent end movement thereof.
